UNITED STATES PATENT OFFICE.

ALFRED WILLIAM BENNIS, OF BOLTON, ENGLAND.

POWER-PRODUCING SYSTEM.

Application filed March 23, 1920, Serial No. 368,184, and in England March 12, 1919.

(GRANTED UNDER THE PROVISIONS OF THE ACT OF MARCH 3, 1921, 41 STAT. L. 1313.)

This invention relates to improvements in power producing plant using solid fuel including coke ovens, retorts, gas producers or the like having means for the recovery 5 of distillates or by products and also including conveyors, elevators or other labour saving appliances, mechanical stokers and so forth which require for their driving, auxiliary apparatus.

10 In contra-distinction to certain power producing systems where the steam necessary for the carbonization of the fuel in the gas producers or the like has been obtained as "bleed steam" from the steam supply to the 15 main turbines or other main generating plant whereas in the arrangement of the present invention steam for such purposes is obtained from the exhaust piping from the engines driving the auxiliaries of the 20 plant.

Such supply can be augmented by "bleed steam" when and only when, according to the present invention, pressure of this "bleed steam" rises above a predetermined point.

25 The invention is more particularly described with reference to the accompanying diagrammatic drawings in which:

Figure 1 is a diagram of a complete power system or plant,

30 Figure 2 is a view on an enlarged scale of a modified coking device or retort, and the devices for conveying coke from producer to grate under boiler or alternatively to another discharge point.

35 Figure 3 is a similar view of a modification,

Figure 4 is a section on the line A—B of Fig. 2.

40 Fig. 5 is a detail diagrammatic section of the automatic valve.

Fuel such as coal is fed to one or a group of retorts, coke ovens or the like 1, by means of a fuel feeder 2, this retort or coking chamber may have if desired as shown, a steam jacket 3. Low pressure superheated steam passes into this retort, through a row of ports 4 communicating with a low pressure superheated steam main 5, having a pressure relief valve 6. The coked fuel

passes continuously out of the retort and 50 the distillate passes away into a pipe 7.

Unlike usual forms of coking retorts, ovens or the like services, in the present invention a gas seal or its equivalent is produced at the lower part, by means of which the 55 escape of any portion of the distillate or the steam (if used) will be substantially prevented at the discharge point of the retort, and consequently also unpredetermined entrance of air or gas from the outside of 60 the retort inwardly. This gas seal may consist of an air or water cooled rotating drum 8 (Fig. 2) which will allow of a continuous discharge of coked product whilst preventing any substantial flow of gas or 65 again either additionally or alternatively the discharge end of the retort may be provided with an elongated extension 9, water jacketed if desired, and provided with means such as pipes 10, 11, 12, for allowing con- 70 trollable amounts of steam to enter as a baffling or pressure steam preventing escape of gas or steam outwardly.

In a modified form of the device the mass of coked fuel in the retort is adapted to 75 leave this retort through a water seal 13 (Fig. 3) which may serve the double purpose of generating the coke, acting as a water seal and generating steam, which steam can be led away through a steam main 80 14 to a low pressure turbine 15. This latter may be arranged in series with a high pressure turbine 16, so that exhaust from this latter can also feed it. A stop valve 85 17, is provided to shut off the pipe 14 from the steam from the turbine 16, when the particular retort 1 is not in use. After passage through the low pressure turbine 15, the water from the hot well of the condenser 18, may be used in the power system 90 19, represents any form of useful device such as an electric dynamo from the turbines. Steam from the main 14 may be led to a pipe 20 for heating boiler feed water, for 95 instance in a device 21 of any usual known type.

The level of the water in the seal 13, may

be maintained constant by an automatic ball-cock 22 or the like controlling a water inlet 23. Where the fuel contains sulphur means for neutralizing the acidity of the water may be used.

The coked fuel may be discharged as above indicated by a rotating drum or again by means of a travelling platform or the like 24 comprising metal links, steam or air 10 cooled.

The air inlets to the sealing chamber as described above, may be fed from pipes 25, communicating with the same main 26, as feeds the compressed air furnace 27, fed 15 with the coked fuel. This compressed air is supplied by a forced draught fan 28 driven by a steam auxiliary 29, exhausting steam into an auxiliary exhaust steam bus line or main 30, and fed from the high pressure 20 steam main 31. This steam main receives steam from the superheater 32, of the boiler 33, heated by the said furnace 27 and is maintained at substantially constant pressure.

The furnace 27 may comprise a chain 25 grate or similar stoker 34. This grate may conveniently be of the type of British patent application No. 5,542 of 1917 A. W. Bennis.

The boiler and grate are placed in a suitable position for receiving the coked or partially coked fuel as it is delivered, so that the boiler and grate form a structural or operating part of the retort or the like 1. It is preferred to employ a grate or mechanical stoking bars having adjustable 30 speeds of travel so that the relation or rate of feed between the conveying device, drum or the like discharging device of the retort 1, to the grate or stoker may be adjusted one to the other so that the thickness of fire 35 on the chain grate may be varied and may be adjusted to suit the characteristics of the fuel. Any known type of draught may be used.

The highly superheated steam supply to 40 the main 5, for the carbonization of the fuel is obtained either from a superheater or any desired independent boiler which may be provided with automatic means for the control of the superheat or this may be arranged 45 as at 35, damper plates 36, being provided to control the passage of the furnace gases from the furnace 27 through the by-pass flue in which it is situated. The steam to supply this superheater 35, is taken from a 50 number or all of the several steam driven auxiliaries.

The boiler flue 37 is connected to a boiler feed water economizer 38 and a service hot water economizer 39. The flue gases are 60 drawn away by an exhauster 40 driven by a turbine 41 or the like prime mover receiving steam from the pipe line 31 and exhausts into the main 30.

The gases from the retort 1 pass from the 65 pipe 7, into a combined condenser and cooler

42, having a sump 43, from which distillates are collected for further treatment or sale. In order to assist the flow of the distillate through the condensing, scrubbing and other by-product recovery apparatus a 70 gas exhauster 44 is connected to the condenser or the like plant 42 which passes the gases to final cooling and stripping apparatus 45 and 46, the stripped gas being led away by a pipe 47 to be combusted at any 75 place desired for power, heating or other purposes. The exhauster 44, of each retort 1, or group of retorts or like plant is operated in unison with the other exhauster 76, fans or similar devices operating in combination so that the amount of highly superheated steam when employed for carbonization may be maintained at an appropriate proportion to the amount of distillate withdrawn from the retort or the like device 1. 85

Water from the condensing water discharge sump 48, or other convenient place is led by pipe 49 to a suction pump 50 sending it through pipe 51 to the condenser and cooler 42 where it is heated, and from whence it passes by pipes 52 to the economizer 39 mentioned above, after which it is passed into a hot water service main 53 to be put to any desired industrial use. This service main 53, is also fed from the pipe 54 90 connected to the bleed-steam heater 55 receiving water from the delivery pump 50 and bleed steam from the bleed steam exhaust bus line or pipe 56.

In order to secure the utmost reduction of 100 initial cost of plant and to attain a maximum operating economy it is preferred to employ turbine generators for the generation of electric energy which may be secured from the combined power plant. If 105 in sizes larger than 15,000 kilowatt generating capacity turbogenerators of the compound type may be used, each unit comprising a high pressure turbine 57 and a low pressure turbine 58, driving the generator 59. The turbines 57 and 58 are connected by a connecting pipe 60 which is provided with an outlet pipe 61 having an atmospheric relief valve 62 and connected to a pipe 63 for the supply of bleed steam 110 when desired for the feed water heater 64, and service water heater 55, and further as will be set forth below.

In order to obtain maximum reliability 115 of the power plant and to facilitate the starting up of the engine or electric generating equipment in the event of a temporary interruption of the electric service from such equipment by reason of an accident, it is preferred to use steam driven auxiliaries 120 for the general auxiliary power requirements of the combined plant such as steam driven condensing water circulating pump 65, taking water from the supply 66 and passing 125 it to the pipe 67 leading to the main con- 130

deniser 68 for the low pressure turbine 58, the steam driven air pump 69 for the condenser 68, the steam driven hot well pump 70, for the hot well 71, of the condenser 68, which passes the hot water to the feed water heater 64 through pipe 72, the steam driven boiler feed pump 73 taking water from the heater 64 and passing it through pipe 74 to the boiler feed water economizer 38 and thence by pipe 75 to the boiler 33, the steam driven hot water service pump 50 and the exhaust steam circulator 76, steam driven fan 28 and exhauster 44, and the like auxiliaries, the driving engines being preferably 15 non-condensing steam turbines.

The auxiliary steam exhaust bus pipe 30 receives exhaust steam from all these auxiliaries, and this pipe supplies exhaust steam through pipe 77 to steam circulating pipes 20 79 at the side of the grate and other parts to be cooled to the low pressure steam superheater 35 and thence by pipe 5 to the retort 1, for the carbonization of the fuel.

Any excess of steam not so required may 25 be passed into a "bleed" steam exhaust bus line 56 from whence it may pass into the low pressure section of any or all of the turbines or turbo-generators or it may be used to heat the feed water or alternatively 30 the before mentioned service water or both as above described, or in the case of emergency the exhaust steam in the pipe line 30 may be discharged directly into the atmosphere by conduit 80 controlled by automatic 35 devices such as the automatic valve 81. This delivery of steam from the exhaust steam main 30 to the bleed steam bus line 56 occurs through the check valve 85 through the 40 valving means indicated at 85 comprising the check valve and the manually controlled valve in series therewith.

In order to provide for emergency such as 45 a stoppage of the supply of exhaust steam to the auxiliary exhaust bus line 30 and in certain cases for the purpose of maintaining continuity of the supply of steam to the high temperature superheater 35 for the process of carbonization, an emergency steam connection 83 is provided between the high 50 pressure main steam supply 31 and the steam line 56, and in this connection 83 an automatic reducing valve 84 is placed so that whenever steam pressure in the pipe 56 falls below a predetermined value, then the valve 55 84 will open to the high pressure steam supply to maintain a constant steam supply pressure in the pipe 56.

It will be noticed that an automatic valve 55 is arranged between the auxiliary exhaust bus line 30 and the bleed steam exhaust bus line 56 whereby steam from the auxiliary bus line 30 is passed into the pipe 56 whenever the pressure of steam in this latter falls below a predetermined desired

limit as needed for heating the feed water 65 or the hot water service system.

The automatic reducing valve 84 may be of any desired type, for example, that shown in Fig. 5, in which, when the pressure in the bus line 56 has fallen to a certain extent, and the pressure in the exhaust pipe line 30 is insufficient to supply the demand, this automatic valve 84 will open to permit the steam to flow from the high pressure steam main 31 as hereafter stated; as shown 70 in Fig. 5, such a valve may have a valve head 84^a held upon its seat by the weight 84^c which may be regulated by the addition of disks as desired: the spindle 84^b of this valve passes through a suitable packing joint 80 84^d. The method of operation is obvious; and it will be understood that any other similar construction may be employed.

I declare that what I claim is:—

1. A power producing plant comprising a 85 steam prime mover, a plurality of steam driven auxiliaries, to said prime mover, a boiler supplying steam thereto, a furnace heating said boiler, a gas producer, means to pass heat fuel to said producer, means 90 to pass coke from said gas producer to said furnace, an exhaust pipe common to said steam driven auxiliaries, means to pass steam from said exhaust pipe to said gas producer to carbonize the fuel therein, a 95 bleed steam pipe to take off steam from the prime mover to heat water and an automatic valve on said steam pipe so that steam may 100 pass in one direction from the exhaust pipe of the auxiliaries to the bleed steam pipe whenever the pressure in this latter falls below a predetermined value.

2. A power producing plant comprising a steam prime mover, a plurality of steam driven auxiliaries to said prime mover, a 105 boiler supplying steam thereto, a furnace heating said boiler, a gas producer, means to pass heat fuel to said producer, means to pass coke from said gas producer to said furnace, an exhaust pipe common to said steam driven auxiliaries, means to pass steam from said exhaust pipe to said gas producer to carbonize the fuel therein, a high pressure steam main, a reducing valve 110 on said high pressure steam main, a bleed steam pipe connected to said reducing valve for passing steam to heat water and an automatic non-return valve between said bleed steam pipe and the exhaust pipe of the auxiliaries so that steam may pass in 115 one direction whenever the pressure in the bleed steam pipe falls below a predetermined value.

3. A power producing plant comprising a steam prime mover, a plurality of auxiliaries, condensing steam turbines driving said auxiliaries, a boiler supplying steam thereto, a furnace heating said boiler, a gas pro-

4 ducer, means to pass heat fuel to said producer, means to pass coke from said gas producer to said furnace, an exhaust pipe common to said steam driven auxiliaries, 5 means to pass steam from said exhaust pipe to said gas producer to carbonize the fuel therein, a bleed steam pipe to take off steam from the prime mover to heat water and an

automatic valve on said steam pipe so that steam may pass in one direction from the exhaust pipe of the auxiliaries to the bleed steam pipe whenever the pressure in this latter falls below a predetermined value. 10

In witness whereof, I have hereunto signed my name.

ALFRED WILLIAM BENNIS.
